UNITED STATES PATENT OFFICE.

MELANCTHON STERNER, OF PHILADELPHIA, PENNSYLVANIA.

SHAVING-CUP.

1,012,474.

Specification of Letters Patent.

Patented Dec. 19, 1911.

Application filed October 1, 1910. Serial No. 584,904.

To all whom it may concern:

Be it known that I, MELANCTHON STERNER, a citizen of the United States of America, residing at Philadelphia, in the county of 5 Philadelphia and State of Pennsylvania, have invented new and useful Improvements in Shaving-Cups, of which the following is a specification.

The invention relates to a shaving cup and 10 more particularly to the class of combined cups and powdered soap holders.

The primary object of the invention is the provision of a cup of this character in 15 which powdered soap may be held thereby, and a predetermined quantity thereof may be delivered into a water reservoir so that the soap will not contact with the water contained within the reservoir or float thereon, thus enabling a shaving brush to be dipped 20 into the receiver for the accumulation of the desired quantity of water and soap for the purpose of lathering the face for shaving purposes.

Another object of the invention is the provision of a cup of this character in which powdered soap and water may be conveniently held for ready access by the user of the cup to enable the proper lathering of 25 the face for shaving purposes.

A further object of the invention is the provision of a cup in which there is arranged a plurality of separable sections or 30 reservoirs, one being for the purpose of receiving powdered soap and the other for receiving water, the reservoir for the soap having a communication controlled by 35 means of a valve so that a given quantity of powdered soap may be delivered into the water receiver but not in contact with the water held therein, thus enabling the dipping 40 of the brush into the soap and water independently of each other, thereby assuring the collection of a definite quantity of water and soap upon the brush for lathering purposes in shaving.

A still further object of the invention is the provision of a cup of this character, which is simple in construction, reliable and efficient in operation and inexpensive in 50 manufacture.

With these and other objects in view, the invention consists in the construction, combination and arrangement of parts as will be hereinafter more fully described, illustrated in the accompanying drawings and

pointed out in the hereunto appended claims.

In the drawings:—Figure 1 is a side elevation of a cup constructed in accordance with the invention. Fig. 2 is a similar view 60 showing a portion of the body of the cup broken away. Fig. 3 is a sectional view on the line 3—3 of Fig. 2, looking in the direction of the arrow. Fig. 4 is a sectional view on the line 4—4 of Fig. 2, looking in the direction of the arrow. Fig. 5 is a side elevation of the water reservoir, the same being partly broken away.

Similar reference characters are employed to designate corresponding parts throughout 70 the several views of the drawings.

Referring to the drawings by numerals, the cup comprises a cylindrical body 10 having a circular outwardly flared base supporting flange 11 at its bottom, the body being divided into independent upper and lower compartments 12 and 13 by means of a horizontal partition 14, the compartment 12 being designed to receive powdered soap, while the compartment 13 is designed to receive 80 a water font or reservoir, as will be hereinafter more fully described.

Detachably engaged with the upper edge or the open end of the body 10 is a removable cap or lid 15, the latter serving to close 85 the compartment 12 for the preservation of powdered soap when confined therein. The body 10 at one end thereof is cut away to form a suitable opening communicating directly with the compartment 13, and into 90 which is detachably fitted a soap font or reservoir comprising a cylindrical cup-like body 16, the same being formed at its bottom with a semi-circular shaped base-supporting flange 17 adapted to overlie a portion 95 of the base supporting flange 11 of the body 10 on introducing the font or reservoir into the compartment 13, the bottom of the body 16 of the font or reservoir being adapted to rest upon the bottom of the body 100 10 on the interfitting thereof.

The body 10 is provided with a loop handle 18 and also the body 16 is provided with a similar handle 19, the handles being designed to permit the carrying of the cup 105 and also the removal of the water font or reservoir 16 at will. Within the body 16 of the font or reservoir and suitably secured to the side wall thereof spaced from the bottom of the same is a sector shaped corrugated 110

gated catcher pan or tray 20, the same being upwardly curved and is adapted to receive the powdered soap delivered from the compartment 12 in the body 10 in a manner as 5 will be hereinafter more fully described.

In the partition 14 within the body 10 is formed a discharge opening 21, the same being directly above the plane of the catcher pan or tray 20 in the water font or reservoir, 10 and this opening is normally closed by a cut-off slide valve 22, the same being connected to the partition 14 by means of a pivot 23, and the slide valve 22 is provided with an outwardly extending finger lever 24, the latter working in a suitable elongated slot formed in the body 10 for the convenient manipulation of the valve 22 by the user of the cup. On the opening of the valve 22 the powdered soap held within the compartment 12 will be discharged through the opening 21 onto the pan or tray 20 in the water font or reservoir 16 where it may be collected by a shaving brush after being dipped into the water contained within the 25 font or reservoir. In the filling of the font or reservoir 16 with water a given quantity is introduced therein so that the level of the water will not stand above the free edge of the catcher pan or tray 20, thereby obviating 30 the possibility of the influx of water into the said pan or tray.

Connected with the pivot 23 and arranged within the compartment 12 is a swinging agitator 25, the same being formed with a 35 finger lever 26 projecting outwardly through a suitable guide slot provided in the side wall of the body 10, the finger lever 26 being bent whereby it will lie in close relation to the finger lever 24, thus enabling both of 40 said levers to be simultaneously moved by the user of the cup. This agitator 25 disintegrates or loosens the compacted quantity of powdered soap within the compartment 12 so that upon opening of the valve 22 the 45 same will freely discharge through the opening 23 into the catcher pan or tray 20 within the water reservoir or font.

In the use of the shaving cup the water font or reservoir 16 is removed from the 50 body 10, whereupon a definite quantity of water is introduced into the said font or reservoir; then it is replaced within the body 10, and the user manipulates simultaneously the finger levers 24 and 26, thus shifting the 55 valve 22 from the opening of the vent 21 whereby a quantity of powdered soap within the compartment 12 in the body 10 will be delivered through the vent 21 onto the catcher pan or tray 20 in the reservoir or font 60 16, and the latter is again removed from the body 10, thus enabling a person to dip a shaving brush into both the water within

the reservoir or font and the powdered soap upon the tray or pan 20 for the lathering of the brush for shaving purposes. 65

Having thus described the invention what is claimed as new is:—

1. A cup of the character described, comprising a hollow body having an annular flange at its bottom forming a supporting base and provided with an opening in one side above said base, a partition disposed transversely in the body intermediate its length and having a discharge orifice, a cup removably fitted in the opening in the side 75 of the said body and normally resting upon the bottom of said body, the body and cup each having a handle, a slide pivoted to the partition and working beneath the same to open and close said discharge orifice and 80 having an arm projecting exteriorly of the body within the handle thereon, an agitator element pivoted above the partition and having an arm extending exteriorly of the body in normal alinement with the arm of the 85 said slide, and a fluted tray mounted within the removable cup spaced from the bottom thereof in the path of the orifice in the partition.

2. A cup of the character described, comprising a hollow body having an annular flange at its bottom forming a supporting base and provided with an opening in one side above said base, a partition disposed transversely in the body intermediate its 95 length and having a discharge orifice, a cup removably fitted in the opening in the side of the said body and normally resting upon the bottom of said body, the body and cup each having a handle, a slide pivoted to the partition and working beneath the same to open and close said discharge orifice and having an arm projecting exteriorly of the body within the handle thereon, an agitator element pivoted above the partition and having an arm extending exteriorly of the body 100 in normal alinement with the arm of the said slide, a fluted tray mounted within the removable cup spaced from the bottom thereof in the path of the orifice in the partition, a cover telescoping upon said body to close the upper open end thereof, the said base flange being cut into to form a semi-circular shaped seat, and a flange formed on the removable cup correspondingly 105 shaped to said seat and adapted to engage the latter to lie flush with the base flange of the body. 110

In testimony whereof I affix my signature in presence of two witnesses.

MELANCTHON STERNER.
